UNITED STATES PATENT OFFICE.

HAROLD W. BOYD, OF PHILADELPHIA, PENNSYLVANIA.

PAVEMENT.

Application filed February 9, 1925, Serial No. 7,920.

To all whom it may concern:

Be it known that I, HAROLD W. BOYD, a citizen of the United States, residing at Philadelphia, in the county of Philadelphia and State of Pennsylvania, have invented 5 certain new and useful Improvements in Pavement, of which the following is a specification.

My invention relates to improvements in 10 road making and more particularly to street paving contiguous to railway tracks and crossings, and the method of installing the same.

As generally recognized the vibrations of 15 railway track structures under the impact of passing traffic and the alternating periods of pressure and ease, gradually effects a loosened and unsettled condition of the track structure upon the road bed. This 20 condition grows progressively worse until a decided vertical heaving movement of the track structure results. The resulting condition is especially serious in the case of railway track traversing paved streets or 25 road-ways, where the track ties are inaccessible for frequent tamping and for reballasting of the road bed. The heaving of the cross ties disturbs the street paving causing upheaval of the paving material 30 at some places and sinking of the pavement at other points until such pavement becomes uneven, broken and finally destroyed. The frequent tearing up of street paving adjacent to the track for track repair 35 purposes results in patch work paving unsightly in appearance and frequently in uneven and otherwise objectionable pavement areas.

To overcome these difficulties there is contemplated in the present invention a street paving construction for railway crossings and track structures, wherein the pavement is supported wholly independent of the cross ties and other track structures, permitting 45 a limited amount of movement of the track structure wholly independent of the adjacent street paving and without subjecting the latter to stresses and strains. To this end the surface pavement is bridged over 50 the cross ties and other underground structure being supported upon piers wholly independent of the embedded railway track construction. While the surface paving overlies the fill material between the track 55 rails and on either side of the track as is

usual, the foundation for such surface paving is afforded solely by spaced piers located intermediate succeeding cross ties so that the weight of the paving is not sustained directly by the cross ties as in the usual street paving constructions. To the contrary the cross ties and railway track construction may vibrate or be permitted a limited amount of heaving movement upon the road bed without transmitting such vibrations to the overlying surface pavement. Furthermore, under the present construction if so desired the surface pavement may be formed in removable sections or 60 units, which may be removed to afford access to the road-bed for reballasting and for tamping of the ties or track replacement, which removable sections or units may be replaced in their original position 65 thus restoring the street paving to its original condition with minimum labor and expense for material, leaving the surface paving in as good condition as when new.

The object of the invention is to simplify 70 the structure as well as the means and mode of operation of paving railway crossings and surfaces between and contiguous to railway tracks, whereby such paving construction will not only be cheapened in construction, but will be more efficient, of greater 75 durability, unlikely to become displaced, broken or otherwise damaged by track movement, and unlikely to get out of repair. A further object of the invention is to 80 provide a construction of the character above referred to, applicable to brick or concrete paving, or to wood planking.

With the above primary and other incidental objects in view as will more fully appear in the specification, the invention 85 consists of the features of construction, the parts and combinations thereof, and the mode of operation or their equivalents as hereinafter described and set forth in the 90 claims.

Referring to the accompanying drawings, 95 wherein is shown the preferred, but obviously not necessarily, the only form of embodiment of the invention, Fig. 1 is a perspective view of a paved railway crossing, embodying the present invention, part of the paving being broken away to disclose the underground track structure and foundation piers. Fig. 2 is a transverse sectional view of a railway track and adjacent 100

street paving. Fig. 3 is a somewhat similar view illustrating the paving of a railway crossing. Figure 4 is a sectional view longitudinally of the track illustrating the manner of attaching the reinforced pavement slabs or units to the foundation piers and illustrating the bridging relation of the pavement to the cross ties of the track structure. Fig. 5 is a top plan view of a portion of the railway track showing the relative location of the foundation piers and cross ties, a portion of the piers being provided with girders, to receive a plank cover. Fig. 6 is a longitudinal sectional view of a plank crossing or railway track. Fig. 7 is a transverse sectional view of a planked track. Fig. 8 is a perspective view of a modification.

Like parts are indicated by similar characters of reference throughout the several views.

It is to be understood that the present invention is not limited to any particular type or style of railway track construction. In the drawings there is illustrated a typical railway crossing in which 1—1 are the track rails at the outer sides of which are located the usual easer rails 2—2 while in spaced relation at the inner sides of the track rails 1 are the usual guard rails 3. In the present construction these special track constructions comprising the crossing members are shown resting upon sleepers 4, transversely arranged parallel with the crossing rail. Extending beyond the crossing is the usual railway track construction consisting of the parallel track rails 5, resting upon spaced cross ties 6, which are in turn embedded in the usual ballasted road bed 7. Intermediate the sleepers 4 and cross ties 6, and covering the latter between the track rails and at opposite sides thereof is the usual fill 8 of gravel or other suitable filling material. Ordinarily the surface paving rests wholly upon the ties and such filling material 8 in which the cross ties 6 and sleepers 4 are embedded, so that every vibration and movement of the ties and sleepers are transmitted to the surface paving. In the present construction while the space beneath the surface paving is substantially filled by the body of filling material 8 and while the surface paving overlies and encloses the fill, the surface paving is entirely supported upon foundation piers 9 formed of concrete. These piers 9 extend somewhat below the level of the cross ties and railway track structure and are positioned in spaced relation intermediate the cross ties 6, both intermediate the track rails and outside the track rails between the protruding ends of the ties. Embedded in the foundation piers 9 are studs 10 for attachment of the surface paving. The pavement shown in Figs. 1 to 4 inclusive consists of a succession of reinforced concrete slabs or units 11, which rest

upon the spaced foundation piers 9 and are interengaged therewith by the stud 10. The pavement slabs 11 are provided with openings 12 to receive the studs. The top orifices of such openings 12 are enlarged or counter-bored as at 13 to receive nuts 14, screw threaded upon the anchor studs 10. The openings are then filled with tar or some similar material, which while protecting the nut 14 and affording a uniform surface with that of the slab may be readily removed to permit the removal of the nut 14 and the detachment of the paving slab when necessary. The pavement slabs 11 may be made of any desired thickness or composition of material, and the reinforcement rods 15 shown in Fig. 4 may be variously disposed. These features of construction such as the thickness, strength, character of the concrete mixture and the matter of reinforcement of the paving slabs will be necessarily dictated by the conditions of use, the location of the roadway and the character of traffic passing over such pavement. Obviously, also the foundation piers 9 may be located more or less closely together and the paving slabs 11 may be made of greater or less size. The foundation piers 9 are preferably, though not necessarily, molded in situ. However, if desired, they may be manufactured elsewhere, and transported to the place of use, where they are set in the road bed to an established grade or level, and in predetermined spaced relation. The railway track structure is then laid in the usual manner intermediate the foundation piers 9. After the track is constructed and the road-bed properly ballasted, the fill 8 is made and tamped or rolled to the level of the tops of the cross ties 6, after which the pavement slabs 11 are bolted in place. Should it be necessary at any time to repair the sub-structure of the track, or reballast the road bed or tamp the ties, the paving slabs 11 are detached from the foundation piers and removed to afford access to the track structure. Upon completion of such repairs, the slabs are replaced in their original position, resting upon the foundation piers which insures the return of the pavement to the original grade or level and leaves the surface in its original condition with no appearance of disturbance or ununiformity and patch work characteristics of the usual track repair job. In some locations, such as stations, platforms, in warehouses, and to meet other local conditions, a planked surface may be desired. In such case, girders 16 are laid across the foundation piers 9, and bolted thereto by the anchor studs 10 before described. Surface planks 17 are then nailed to the girders 16, as shown in Figs. 5, 6 and 7. This planking may merely rest on top of the girders 16 to which the planks are nailed as shown in Fig. 7, or such girders

16 may be gained to the under surface of the planking 17, as shown in Fig. 6. In this figure the surface planking 17 are notched or recessed on their under surfaces to fit 5 over the transversely arranged girders 16, which in turn rest upon the foundation piers 9.

As an alternative construction there is shown in Fig. 8, metal plates 18, preferably 10 having their margins slightly upturned at 19 into pan like formation, which rest upon and are secured to the foundation piers 9 and upon which in turn is laid the conventional brick pavement 20 upon a sub-stratum 15 of sand 21, contained in the pan like flanged plate. While this construction does not afford the accessibility for track repair purposes, it serves the other purposes of the invention. Any of the constructions hereto- 20 fore described will permit a reasonable amount of vibration and heaving movement of the track structure, without disturbing or damaging the surface pavement. As is illustrated in the several figures of the drawing, more particularly Figs. 2 and 4, the surface pavement is elevated and bridged 25 over the sub-structure of the track and supported upon the foundation piers independent of the track structure, in such way 30 that the track structure and pavement are isolated from each other.

From the above description it will be apparent that there is thus provided a device of the character described possessing the 35 particular features of advantage before enumerated as desirable, but which obviously is susceptible of modification in its form, proportions, detail construction and arrangement of parts without departing from 40 the principle involved or sacrificing any of its advantages.

While in order to comply with the statute the invention has been described in language more or less specific as to structural features, it is to be understood that the invention 45 is not limited to the specific details shown, but that the means and construction herein disclosed comprises the preferred form of several modes of putting the invention 50 into effect and the invention is, therefore, claimed in any of its forms or modifications within the legitimate and valid scope of the appended claims.

Having thus described my invention, I 55 claim:

1. In a railway track pavement, the combination with a railway track construction, including spaced rails and cross ties, of a plurality of piers located at spaced intervals 60 intermediate the cross ties, and paving slabs removably secured to the piers and bridging the cross ties whereby the pavement is supported independent of the track construc- 65

2. In a railway track pavement, the combination with a railway track construction including track rails and cross ties, of a surface pavement, including a succession of arches bridging the cross ties and supported therebetween, independent of the railway 70 track construction, whereby vibration of the track structure will not be transmitted to the pavement.

3. The herein described method of protecting surface paving of railway crossing and track construction from deterioration due to vibration of the track, consisting in supporting such paving wholly independent of the track construction at spaced intervals and bridging the pavement over the sub-surface track construction thereby permitting vibratory movement of the track construction independent of the pavement.

4. The combination with a railway track construction, including track rails and cross ties, of a surface pavement overlying the cross ties and extending adjacent to the track rails and means for supporting the surface pavement independent of the track structure whereby track vibrations will not 85 be transmitted to the surface pavement.

5. The combination with a railway track construction, including track rails and cross ties, of a surface pavement, comprising a succession of separate independently removable sections, overlying the cross ties and extending adjacent to the track rails, and means for supporting the surface pavement independent of the track structure, whereby track vibrations will not be transmitted 90 to the surface pavement.

6. A railway track construction including track rails and cross ties, paving slabs bridged across the cross ties, and supported therebetween, foundation supports for said 100 slabs intermediate the cross ties, and a body of filling material in which the cross ties are embedded beneath the paving slabs.

7. A railway track construction including track rails and cross ties, a plurality of spaced piers located intermediate the cross ties, bolt studs projecting from the tops of said piers, paving slabs resting upon the piers and bridging the cross ties, said slabs having holes therein to receive the bolt 110 studs, said holes being counter-bored to afford recessed seats for attachment nuts below the surface of the slabs.

8. A railway track construction including track rails and cross ties, a plurality of spaced piers located intermediate the cross ties, and a succession of reinforced concrete slabs detachably connected with the tops of said piers and bridging the cross ties.

In testimony whereof I have hereunto set my hand this 24th day of January, A. D. 1925.

HAROLD W. BOYD.
